CLAIM

The ornamental design for a marker for garment hanger, as
shown and described.

DESCRIPTION

FIG. 1 is a perspective view showing the front, top, and left
side of the marker for garment hanger;

FIG. 2 is a front elevation view thereof;

FIG. 3 is a rear elevation view thereof;

FIG. 4 is a bottom plan view thereof; and,

FIG. 5 is a left side elevation view thereof.

The right side elevation view is omitted. The right side
elevation view is plain and unornamented.
